EYE EXERCISER

Arthur E. Jacobson, Alexandria, Minn.

Application August 14, 1942, Serial No. 454,847

12 Claims. (Cl. 128—76.5)

My invention relates to eye treatment, and has among its objects and advantages the provision of a novel mechanical device for exercising the muscles of the eyes.

In the accompanying drawings:

Figure 1 is a face view of the device;

Figure 2 is an end view;

Figure 3 is an enlarged sectional view of a rotor mechanism;

Figure 4 is a detail view of a light flasher;

Figure 5 is a view taken along the line 5—5 of Figure 3;

Figure 6 is a view of a flasher control;

Figure 7 is a sectional view taken along the line 7—7 of Figure 3;

Figure 8 is a sectional view taken along the line 8—8 of Figure 1; and

Figure 9 is a sectional view taken along the line 9—9 of Figure 3.

In the embodiment selected for illustration, I make use of a stator or frame 10 hingedly connected at 12 with a supporting base 14. The frame 10 may be stamped from sheet metal and is formed with a circular track 16 semicircular in cross section, as illustrated in Figure 8. The frame may also be provided with a strengthening formation 18.

Inside the frame 10 is mounted a rotor unit 20 provided with three wheels 22 running in the track 16. These wheels are spaced as close to one hundred and twenty degrees apart as is possible in the structure of the rotor. The rotor comprises two substantially semicircular housings 24 and 26, see Figure 3. Each housing includes two spaced side walls 28, an interconnecting peripheral wall 30 and a straight wall 32 located between the walls 28 and secured thereto by screws 34. The two straight walls 32 are spaced apart in parallel relationship, and the two housings are fixedly secured into a unitary structure 40 by straps 36 secured to the peripheral walls 26 by screws 38. Each strap is provided with a slot 40 for one of the screws 38 so that the housings may be adjusted to different relatively spaced positions.

Inside the housing 24 is mounted a spring motor 42 which supplies power for turning the rotor inside the frame 10. This motor comprises a spring 44 having one end fixedly secured to a pin 46 anchored to the walls 28 and its other end fixedly secured to a winding shaft 48. To the winding shaft 48 is fixedly secured a ratchet wheel 50 adjacent one face of a sprocket 52 provided with a pivoted pawl 54 engageable with the ratchet wheel 50. The pawl is yieldingly

pressed into engagement with the ratchet wheel 50 through the medium of a spring 56. Thus the spring 44 may be manually wound by imparting clockwise rotation to the shaft 48, as when viewing Figure 3, with the pawl 54 so arranged as to impart counterclockwise rotation to the sprocket 52 through unwinding of the spring.

Meshing with the sprocket 52 is a smaller sprocket 58 fixedly secured to a friction wheel 60 engageable with one of the wheels 22 to impart rotation thereto for driving the rotor. The sprocket 58 and the friction wheel 60 are rotatably carried by a support 62 into which an adjusting screw 64 is threaded for moving the friction wheel into and out of turning engagement with the wheel 22. This screw is rotatably mounted in the straight wall 32 of the housing 24 but is restrained from relative longitudinal movement so that the friction wheel may be shifted toward and away from the wheel 22 through rotation of the screw.

The sprocket 52 meshes with a sprocket 66 mounted on a shaft 68 rotatably journaled in the walls 28. This sprocket is fixedly connected with a larger sprocket 70 meshing with a sprocket 72 connected with a shaft 74 rotatably supported in a bushing 76 pressed into an opening in the straight wall 32. One end of the shaft 74 is fixedly secured to an insulative body 78, as by a pin 80. The insulative body 72 serves as a mount for a rotary lamp structure 82, which lamp structure rotates about an axis at right angles to the axis of rotation of the rotor.

The rotor lamp structure 82 comprises two lamp sockets 84, see Figure 7, at the outer ends of the two arms 86 of the rotary lamp structure. Each of the arms 86 includes a conductor bar 88 having electrical engagement with the central contact of its respective lamp 90. A square sleeve 92 electrically connects the two bars 88, which sleeve is secured to a square pin 94 embedded in the insulative body 78.

Each conductor bar 88 also includes a second conductor bar 96 having electrical connection with the conductor sleeve 98 on its respective lamp 90, the socket 84 being in current conducting engagement with the conductor bar 96. An insulative body 100 is positioned between both bars 88 and their respective conductor bars 96 and the parts secured into a unitary structure through tightening of setscrews 102.

The two conductor bars 96 are electrically connected with a metallic band 104 through which the pin 80 of Figure 3 is extended. Thus the

conductor bars 96 are electrically connected with the shaft 74, the bushing 76 and the housing 24. The wall 32 of the housing 26 is of insulating material and is provided with a bearing 106 for supporting the tapered end 108 on the body 110 fixedly attached to the square pin 94. On the body 110 are mounted two cross arms 112 and 114. The cross arm 114 lies on the cross arm 112, and the two arms are frictionally connected with the body 110 to rotate therewith as a unit, but the bodies may be adjusted to different relative angular positions when manually rotated on the body. Spaced insulative bodies 116 are attached to the arm 112 and conductor bodies 118 are attached to this arm between the bodies 116. The bodies 116 and 118 terminate in flat planes lying flush with the arm 114. The insulative bodies 116 on opposite sides of the body 110 are equally spaced from the axis of the body, which is also true of the conductor bodies 118.

A slidable contact 120 is mounted on the wall 32 of the housing 26 for conducting engagement with the arms 112 and 114. This conductor is slidably guided in a loop 122 attached to the wall 32 and is provided with a pin 124 to facilitate adjustment of the contact toward and away from the axis of the body 110. The contact 120 is in electrical engagement with a sleeve 126 secured to the wall 32, which sleeve is connected with a fixed contact 128.

A resistance 130 is mounted on a fixed insulative body 132 attached to the wall 32, which resistance is engageable by a slide contact 134 having conducting engagement with the fixed contact 128. A pin 136 is attached to the slide contact 134 to facilitate adjustment thereof.

To one end of the resistance 130 is connected a resilient conductor 138 respectively engageable with one terminal of each dry cell 140, the other terminals of these cells being electrically connected with one wall 28 of the housing 26, as at 142.

Meshing with the sprocket 70 is a sprocket 144 fixedly connected with a larger sprocket 146, both of which are mounted on a shaft 148 rotatably supported on one wall 28 of the housing 24. The sprocket 146 meshes with a sprocket 150 secured to a shaft 152, see Figure 5, rotatably journaled in the walls 28. This shaft is split and separated at 154 to frictionally support a shaft 156 having fan blades 158 attached thereto. Operation of the spring motor 42 imparts rotation to the shaft 152, and the speed of the motor may be regulated by adjusting the fan blades 158 to different angular positions. Thus the fan blades constitute an air reaction governor for controlling the speed of the spring motor. An opening 160 is provided in each of the walls 28 of the housing 24 for the free circulation of air.

Referring to Figure 2, the base 14 is provided with an arm 162 having a series of openings 164 for selective reception of a bolt 166 passing through an opening in a bar 168 attached to the frame 10. Normally the frame 10 is in the vertical position of Figure 2, but the frame may be pivoted to and latched in different angular positions with respect to the vertical.

Two flanges 170 are attached to the frame 10 for selective reception in slots 172 in a septum 174. This septum is provided with concaved edges 176 conforming to the curvature of the frame 10 to have close fitting engagement therewith. The septum is so contoured as to have

different effective lengths when connected in its respective positions with the frame.

In operation, the lamps 90 rotate as a fixed unit through the space between the two walls 32. These lamps may be periodically flashed by adjusting the contact 120 to engage the conducting bodies 118. The lamps may be caused to burn continuously by shifting the contact 120 to a position near the body 110. The flash duration of the lamps is also controllable through shifting of the contact 120 toward and away from the axis of the body 110.

It will thus be seen that I have provided an apparatus for assisting patients in exercising their extrinsic and intrinsic muscles through the medium of the lights which move along predetermined paths, thereby stimulating monocular abduction, infra-duction, supra-duction, intra-duction and extra-duction.

20 The lamps may be caused to flash at predetermined stationary or progressively changing points to aid in such stimulation without causing a condition of diplopia to take place. The septum is adjustable so as to insure monocular vision with respect to each lamp. The septum induces the extrinsic as well as the intrinsic muscles of each eye to focus on its own lamp regardless of the position of the other lamp. The intensity of the moving lamps may be controlled through adjustment of the contact 134. Infra-duction or supra-duction may be increased or decreased for either or both eyes through tilting of the apparatus about the axis of the hinge 12. By removing the septum and employing one lamp only, both eyes may be focused on the one moving or flashing lamp to develop binocular coordination and fusion of the image.

Without further elaboration, the foregoing will so fully illustrate my invention, that others may, 40 by applying current knowledge, readily adapt the same for use under various conditions of service.

I claim:

1. An eye exercising device comprising a circular track, a rotor guided by the track and having a rotary driving means arranged in tractive engagement with said track, a motor carried by said rotor, a driving connection between the motor and said means, lamps, a support for said lamps mounted for rotation on said rotor about an axis at right angles to the axis of rotation of the rotor, a driving connection between the motor and said support, an electric circuit connected with said lamps, and a switch means connected in the circuit and carried by said rotor and actuated through rotation of said support for intermittently energizing the lamps.

2. The invention described in claim 1 wherein said rotor is provided with a fan for controlling the speed of the rotor, and a driving connection between said fan and the motor.

3. The invention described in claim 1 wherein said motor comprises a windable spring means.

4. The invention described in claim 1 wherein said rotary driving means comprises a wheel frictionally engaging the track, a friction wheel driven by the motor, and means for moving the friction wheel into and out of driving engagement with said first-mentioned wheel.

5. The invention described in claim 1 wherein there is interposed an adjustable resistance in said circuit to vary the illuminating intensity of said lamps.

6. An eye exercising device comprising a circular track, a rotor guided by the track and having a rotor driving means coacting with the track

to impart rotation to the rotor, a motor carried by said rotor, a driving connection between the motor and means, a lamp, a support for said lamp mounted for rotation on the rotor about an axis at right angles to the axis of rotation of the rotor, a driving connection between said motor and the support, an electric circuit including in part said rotor and the support for energizing the lamp, a switch means comprising a first contact carried by the rotor and connected in the circuit, and a second contact connected in the circuit and carried by the support for intermittently engaging the first contact through rotation of the support.

7. An eye exercising device comprising a circular track, a rotor guided by the track and having a rotor driving means coacting with the track to impart rotation to the rotor, a motor carried by said rotor, a driving connection between said motor and means, lamps, a support for said lamps mounted for rotation on the rotor about an axis at right angles to the axis of rotation of the rotor, a driving connection between said motor and the support, an electric circuit including in part said rotor and the support for energizing the lamps, a switch means comprising a first contact carried by the rotor and connected in the circuit, and a second contact connected in the circuit and carried by the support for intermittently engaging the first contact through rotation of the support.

8. The invention described in claim 6 wherein there is provided a third contact on said support electrically engaging the second contact and adjustable relatively to the second contact about the axis of the support.

9. The invention described in claim 7 wherein there is provided a third contact on said support electrically engaging the second contact and adjustable relatively to the second contact about the axis of the support.

10. The invention described in claim 7 wherein there is provided a third contact on said support electrically engaging the second contact and adjustable relatively to the second contact about

the axis of the support, said third contact having insulated areas spaced one from the other and radially from the axis of the support to divide the third contact into a plurality of contact areas, and said first contact being movably mounted for adjustment toward and away from the axis of the support for selective engagement with said conducting areas.

11. The invention described in claim 7 wherein there is provided a third contact on said support electrically engaging the second contact and adjustable relatively to the second contact about the axis of the support, said third contact having insulated areas spaced one from the other and radially from the axis of the support to divide the third contact into a plurality of contact areas, said first contact being movably mounted for adjustment toward and away from the axis of the support for selective engagement with said conducting areas, and a resistance interposed in said circuit and having a slide contact electrically engaging said first contact.

12. The invention described in claim 7 wherein there is provided a third contact on said support electrically engaging the second contact and adjustable relatively to the second contact about the axis of the support, said third contact having insulated areas spaced one from the other and radially from the axis of the support to divide the third contact into a plurality of contact areas, said first contact being movably mounted for adjustment toward and away from the axis of the support for selective engagement with said conducting areas, a resistance interposed in said circuit and having a slide contact electrically engaging said first contact, said rotor comprising a first housing enclosing said motor, a second housing electrically connected with the first housing, said first housing being electrically connected with said switch means, said first housing and the second housing comprising in part said electric circuit, and an electric battery means enclosed in the second housing grounded thereto and connected with said resistance.

ARTHUR E. JACOBSON.
